UNITED STATES PATENT OFFICE.

HAROLD ST. J. GUILD, OF JAMAICA PLAIN, MASSACHUSETTS.

ELASTIC WEBBING.

Application filed November 25, 1925. Serial No. 71,354.

This invention relates to the manufacture of webbing, more especially elastic webbing.

It is the chief object of the invention to improve both the structure and methods of making webbing of this character with a view to reducing the expense of manufacture, while still providing an entirely satisfactory article. It has been customary heretofore to manufacture elastic webbing by using a single shuttle for each web. In my Patent No. 1,524,820, dated February 3, 1925, I have disclosed a process of making webbing in which two shuttles are used in each web so that the filling can be introduced twice as fast as in prior processes. The process disclosed in said patent produces a webbing which is very satisfactory for some classes of goods, particularly for suspenders, and the like. The present invention aims to devise a process in which the high rate of production and economy of manufacture of my earlier process will be obtained, and which shall be adapted for the manufacture of a wider variety of goods than those for which the process of my patent is more particularly suited.

The nature of the invention will be readily understood from the following description when read in connection with the accompanying drawings, and the novel features will be particularly pointed out in the appended claims.

In the accompanying drawings,

Figure 1 is a diagram showing the shed and shuttle arrangement which preferably is used in making webbing according to the present invention;

Fig. 2 is a diagrammatic cross-sectional view taken substantially on the line 2—2, Fig. 1;

Fig. 3 is a view similar to Fig. 2 but illustrating a further step in the weaving operation;

Fig. 4 is a diagrammatic plan view showing the structure of the fabric at one selvage edge of the goods with the threads and strands spread apart; and

Fig. 5 is a cross-sectional perspective view illustrating the fabric structure in a conventional way.

Referring to the drawings, Fig. 1 illustrates an arrangement which may conveniently be used in practicing the process at present preferred with the aid of a loom of the usual construction. As here shown, the warp threads and the strands of rub-

ber are arranged to form two sheds, one above the other, with the strands of rubber occupying an intermediate position and forming the bottom of the upper shed and the top of the lower shed. These strands of rubber (commonly called "rubbers") are drawn from a beam 3. The warp threads may be supported in any convenient manner, and they are guided over the roll 6 to the harnesses. The upper and lower shuttles are indicated at 1 and 2, respectively, and the breast roll at 7.

Preferably the two shuttles are projected through the sheds simultaneously in opposite directions, although they may be propelled simultaneously in the same direction, if desired. The harness motion, of course, will depend upon the pattern which is being woven. With this arrangement two strands of filling are inserted in the fabric at each pick, one strand in each shed. Consequently, the filling can be laid twice as rapidly as in the more common processes of weaving with a single shuttle.

Throughout the body of the goods the strands of rubber A remain stationary, that is, they are not moved up or down across either shed, their only movement being a feeding movement as the web is taken up.

The diagrammatic view, Fig. 2, assumes that a plain weave is being made, and the warp threads which form the top of the upper shed at a given instant are indicated at B, and those which form the bottom of the lower shed at said instant are indicated at C. The strands of rubber A and the gut threads D which are associated with them, are relatively stationary and separate the two sheds from each other. The chief problem in weaving webbing with two shuttles is to produce a satisfactory edge. The manner in which this is done according to the present invention is clearly illustrated in the drawings. Referring to Fig. 2 it will be seen that additional strands of rubber E and F are located at the opposite ends of the sheds, one strand at each end, and in the arrangement shown one strand is up while the other is down, although they may be moved up and down in unison. Positioned immediately beside the respective strands of rubber are wires e and f, each operated by the harness for the respective strands of rubber E and F so that each moves up or down across both sheds in unison with its respective rubber.

Starting with the warp threads and the rubbers arranged as shown in Fig. 2, let it be assumed that the first pick occurs. The upper shuttle 1 in its flight through the 5 upper shed lays the filling thread O, while the lower shuttle 2 inserts the filling P in the lower shed. The sheds then change, the warp threads B and C reversing places and moving into the positions shown in 10 Fig. 3. At the same time the edge rubbers E and F move across both sheds, the wires e and f moving with them. This results in partially wrapping the filling threads around the edge strands of rubber E and 15 F and the wires e and f, so that when the next pick occurs, as illustrated in Fig. 3, the filling threads will be wrapped completely around the edge strands of rubber.

As the operations just described are 20 repeated a single ply fabric will be woven of the general character shown. The two filling threads cover the surface of the strands A of rubber through the body of the goods with the filling threads O always 25 lying on one side of said strands while the threads P always lie in the opposite side. Since there are two strands of filling in each 30 pick of the fabric, both filling threads are looped around the edge strands of rubber E and F at the end of each pick. The wires e and f are not long enough to reach 35 from the harnesses to the breast roll but they both terminate a short distance, say, for example, one and one-half or two inches, to the right, Fig. 1, of the beat-up point, and as the fabric is taken up it slips off 40 the ends of the wires. The object in using these wires is to prevent the filling threads, as they wrap around the edge strands of 45 rubber E and F, from binding said strands. In other words, the wires are useful in leaving a looser selvage than otherwise would be made, and such a selvage is desirable in order to produce an edge having the desired degree of elasticity.

This invention is especially applicable to the weaving of light weight webbing such as that used, for example, in garters; and because of the increased production afforded by this process, it effects a substantial economy in the manufacture of these webbings. This process also produces a smooth, round, selvage edge which stretches and contracts equally with the body of the 50 web and is fully as satisfactory to the trade as the webbing made by the usual processes. While there may be some question technically as to the accuracy in designating the goods shown as single ply fabric, still goods of this character are known in the trade 55 by this term.

It will be understood that no attempt has been made to indicate any special pattern or weave, the present disclosure being confined more to the essential features of the

invention. The weave or pattern obviously can be varied as widely as in goods made by prior processes. This process may also be used with the same advantages in the weaving of non-elastic webbings used for 70 straps, belts, and the like, where central warps (ordinarily referred to as padding warps or gut warps) are used in place of the rubber strands and are manipulated in the same way. Consequently, the reference 75 in the foregoing description and in the appended claims to strands of rubber should be understood to include gut warps of the character just mentioned. In making non-elastic webbing the wires e and f would 80 not be used.

Having thus described my invention, what I desire to claim as new is:

1. That improvement in the process of 85 weaving elastic webbing which consists in arranging warp threads and strands of rubber to form two sheds, one above the other, with the strands of rubber forming the top of the lower shed and the bottom of the upper shed, inserting two filling threads in 90 said sheds simultaneously at each pick with one thread in each shed, manipulating warp threads between picks to interlock them with said filling threads and thereby weave a fabric, and moving an additional strand of 95 rubber up or down across both sheds at one end of said sheds between successive picks to cause both filling threads to be wrapped around it at the end of each pick, two adjacent filling threads being passed over and the 100 next two adjacent filling threads passed under said strand of rubber, thereby producing a tubular selvage enclosing said additional strand of rubber.

2. That improvement in the process of 105 weaving elastic webbing which consists in arranging warp threads and strands of rubber to form two sheds, one above the other, with the strands of rubber forming the top of the lower shed and the bottom of the upper shed, inserting two filling threads in said 110 sheds simultaneously at each pick with one thread in each shed, maintaining said strands of rubber relatively stationary, moving warp threads up or down across said 115 sheds between successive picks to interlock them with the filling threads and thereby weave a fabric of the desired pattern, arranging additional strands of rubber at the opposite ends of said sheds, and moving said 120 additional strands up or down across both sheds between successive picks, whereby both filling threads are wrapped around each of said additional strands of rubber at the 125 end of each pick, two adjacent filling threads having been passed over and the next two adjacent filling threads passed under said strands of rubber, thus forming tubular selvages enclosing said additional strands of 130 rubber.

3. That improvement in the process of weaving elastic webbing which consists in arranging warp threads and strands of rubber to form two sheds, one above the other, 5 with the strands of rubber forming the top of the lower shed and the bottom of the upper shed, inserting two filling threads in said sheds simultaneously at each pick with one thread in each shed, manipulating warp 10 threads between picks to interlock them with said filling threads and thereby weave a fabric, moving an additional strand of rubber up or down across both sheds at one end thereof between successive picks, moving a 15 wire with said additional strand and immediately outside of it whereby both filling threads are caused to wrap around said strand and wire at the end of each pick and thereby produce an enlarged tubular selvage.

loosely enclosing said additional strand of 20 rubber, and subsequently withdrawing said wire from said tubular selvage.

4. A strip of elastic webbing comprising a single ply fabric having strands of rubber extending longitudinally thereof in the 25 body of the fabric with two filling threads in each pick of the body portion of the fabric, said filling threads being located on opposite sides of said strands of rubber, an additional strand of rubber at one edge of 30 said strip, and a tubular selvage enclosing said edge strand and composed entirely of filling, both of said filling threads being looped around said edge strands at the end of each pick, two adjacent filling threads 35 lying over and the next two adjacent filling threads lying under said edge strand.

HAROLD ST. J. GUILD.
